LEAD CASTING MACHINE

Ernest S. Morgan, El Cerrito, Calif.

Application November 16, 1950, Serial No. 195,997

6 Claims. (Cl. 22—77)

1

The present invention relates to improvements in a lead casting machine and has particular reference to a machine for casting battery posts and straps, although the principles involved may be applied to the casting of various other relatively small parts.

In casting the parts designated it is customary to provide mold blocks with flat top faces and suitable depressions corresponding in shape to the desired castings and to provide gate blocks adapted for superimposing on the mold blocks and having a pouring basin and pouring holes, through which the molten lead is poured into the mold depressions or cavities. The gate is then moved with respect to the mold to shear the metal at the top surface, and subsequently the castings are removed from the mold manually, while the surplus material clinging to the gate is shaken out of the latter by manual operation.

In the present invention is proposed to provide a machine which performs all of these operations automatically, the mold and the gate being moved in circular courses on spaced vertical axes, in intermittent movements, to pass through various stations, being made to register at one of the stations for the pouring of the lead, and then proceeding individually to different stations for the removal of the finished casting from the mold and for the removal of the surplus material from the gate.

It is further proposed to arrange the molds and the gates in corresponding multiples in the form of turrets, whereby a large number of castings may be carried out in quick succession.

It is further contemplated to provide means for effecting a quick relative movement between the gate and the mold after the pouring operation to shear the metal at the top plane of the mold.

It is further proposed in the present invention to mount the gate with freedom of swinging movement on a vertical plane and to provide suitable guide means whereby the gate is moved to horizontal position as it approaches the pouring station for registry with the mold, and is moved to a vertical position as it approaches another station where means are provided for ejecting surplus material from the gate.

It is a further object of the invention to provide a novel ejecting mechanism for cleaning the gates of the surplus material.

It is further proposed to provide, at a station spaced from the pouring station, a novel means for removing the castings from the molds, which includes means, where battery posts are con-

2

cerned, for partly lifting the posts out of the molds, means for gripping the shanks of the posts and means for lifting the gripping means, for swinging the same sidewise away from the mold and for releasing the gripping means whereby the posts are dropped outside of the machine.

It is further proposed to provide a novel means for automatically removing strap castings from the mold which include means for freeing the straps from the mold and for sweeping the free straps from the surface of the mold.

Further objects and advantages of my invention will appear as the specification proceeds, and the novel features of my invention will be fully defined in the claims attached hereto.

The preferred form of my invention is illustrated in the accompanying drawings, in which

Figure 1 shows a plan view of my machine, with the parts in position for pouring,

Figure 2, a side view, partly in section, of the machine, with the parts in the same position as in Figure 1, and

Figure 3, a view similar to that of Figure 2, with the parts in shearing and casting lifting position.

While I have shown only the preferred form of my invention, I wish to have it understood that various changes and modifications may be made within the scope of the claims attached hereto without departing from the spirit of the invention.

Referring to the drawings in detail, my machine comprises in its principal features two revolvable assemblies or turrets 1 and 2 carrying the molds 3 and the gates 4 respectively and mounted on spaced vertical shafts 5 and 6 respectively, means for intermittently revolving the turrets in opposite directions with intervening periods of rest at designated stations, means at one station 7 for bringing companion molds and gates into registry for pouring operations, means at another station 8 for ejecting surplus material from gates passing through said station, and means at another station 9 for removing finished posts from a mold passing through said station.

In the present instance the machine is shown as having four molds evenly distributed on the first turret and four gates evenly distributed on the other turret, but it is apparent that the number of molds and gates may be changed, as long as they are arranged symmetrically around the turrets and positioned for proper overlapping at the pouring station 7 at designated times. For the purpose of the description it is sufficient to refer to the operation of a single mold

and its companion gate, since the other molds and gates follow the same course. It should be noted, however, that for convenience in operation in the factory some of the molds may be used for casting battery posts and others for casting battery straps which call for a slightly different arrangement.

The turret 1 is in the form of a disc 10 having four molds 3 projecting radially therefrom in evenly spaced relation. Each mold is secured upon the rim of the disc by a projecting flange 11 and bolts 12. Each mold is in the form of a rectangular block having a flat, horizontal top face and having a plurality of depressions or cavities 13 in the upper face, the cavities being shaped to correspond to the shape of the post head to be molded and having downward projecting ports or passages 14 extending to the bottom of the mold block, the diameter of each passage corresponding to that of the post shank. As shown in the present instance, each mold has six cavities, arranged in two parallel rows of three each. The bottom end of each passage is closed by a plunger 15.

The turret 2 is also in the form of a disc 16 having four evenly distributed gates 4 pivoted thereto for swinging motion in vertical planes and for sliding motion in said planes. For mounting the gates 4 I provide four small blocks 17 bolted upon the rim of the disc, each carrying a radially movable rod 18 having a second block 19 mounted thereon, with a spring 19 braced against the first block and a head 20 at the inner end of the rod serving to normally hold the second block against the first block as in Figure 2, but with freedom of outward movement into the position shown in Figure 3.

The gate 4 is pivoted to the second block 18 as at 21, with freedom of swinging motion in an axial plane and comprises a rectangular block having a flat bottom face adapted to overlie the top face of the mold, when the gate and the mold are made to register as at station 1, and is formed, in its upper face, with a pouring basin 22 and downwardly extending ports 23 made to align with the cavities in the mold when the gate and the mold are in positions of registry.

When the mold and the gate are in this position, at the station 1, molten lead may be poured into the basin 22 to flow through the ports 23 into the mold cavities, sufficient lead being usually poured to allow an excess to remain in the ports and possibly in the bottom of the basin 22. To insure a clean cut of the metal at the upper face of the mold, I provide means operative while the turrets remain in their positions, to slide the gate 4 outward for shearing action, this being accomplished by means of a finger 24 pivoted as at 25 and actuated, by any suitable means, for momentarily forcing the gate outward, the spring 19 returning the gate as soon as the pressure of the finger 24 ceases.

After the shearing operation, the revolving movement of the two turrets continues, turret 2 rotating clockwise and turret 1 rotating anti-clockwise. The gate under discussion, after passing through a station 90 degrees from the pouring station, reaches the station 8 opposite the latter station. During this travel the gate is made to gradually drop from the horizontal position it occupied at the pouring to a suspended vertical position. At the beginning of the rotary movement the gate is still supported by the mold, but when these two elements lose contact, the support is taken over by a cam track 26, the gate

having a roller 27 adapted to ride on the track, and the latter being formed to gradually lower the outer end of the gate until the latter reaches a fully suspended vertical position as shown at the extreme right in Figures 2 and 3. A stop 28 may be provided for the roller 27 to catch behind so as to keep the gate from swinging outward during the ejecting operation.

When the gate, with its adhering surplus material, reaches the vertical position, it comes opposite a bracket 29 having a number of push rods 30 slidably thereon, the push rods being mounted to line up with the ports in the gate and being normally retracted by springs 31 bearing on the bracket and on a plate 32 carried by the push rods. A forked member 33, made to straddle a portion of the supporting column 34 for the turret is fixed with respect to the plate 32 and carries, at its inner end, a plate 35 which is acted on by a roller 36 on a swinging arm 37 to push the plate 32 and the push rods 30 outward, for the push rods to enter the ports in the gate and to eject the lead adhering to the latter.

Upon continuation of the revolving movement of the turret 2, a second cam track 38, similar to track 26, again lifts the gate under discussion into horizontal position, until the weight of the gate is taken over by the companion mold of the other turret.

This latter mold, in the meantime, after having received its load of castings at the pouring station, passes in its circular route through two inactive stations and then reaches station 9, at which it is relieved of its load.

The means for removing the finished castings comprises an understructure 40 designed to partly lift the castings so as to bring the heads and part of the shanks of the battery posts above the surface of the mold, and a superstructure 41 which grips the shanks underneath the heads, clears the entire posts off the mold and then moves the posts sidewise to a point outside the machine for final discharge.

The understructure 40 comprises a plate 42 carried by the plungers 15 below the mold and normally urged downward by springs 43 which normally serve to hold the plungers in proper position to make the ports 14 the proper length for charging. The plate 42 has a stem 44 projecting downward therefrom, and when the mold comes to rest at the station 9, this stem is disposed above a plunger 45 which latter is made to rise, in timed relation to the arrival of the mold to lift the stem 44 and the plungers 15 sufficiently far to cause the heads of the posts and portions of the shanks to project above the surface of the mold.

The superstructure 41 comprises a sleeve 46 slidably and revolvable on a fixed vertical shaft 47, an arm 48 projecting from the sleeve, and an open-ended box 49 mounted upon the end of the arm, the box being movable from a position vertically over the mold to a sidewise position away from the mold.

The molds have been shown as containing two lines of posts, each line comprising three. The box is equipped with means for gripping both lines at the same time but, for the time being, I will confine myself to the gripping means for one line of posts. This gripping means comprises two gripping rods 50 mounted in the end walls of the box, near the bottom thereof, and with freedom of sliding motion in slots 51. Opposite ends of each rod have arms 52 projecting therefrom, the arms being pivoted in the end walls near their upper ends as at 53. The arms

at one end of the box are extended to project above the box as at 54.

Spring means, indicated at 55, tend to draw the two gripping rods toward one another, and the gripping rods may be held apart, against the spring action, by means of a locking bar 56, having one end hinged as at 57 and having its free end urged downward by a spring 58, the locking bar having a recess 59 adapted to receive pins 60 projecting from the arms 54 for holding the latter in parallel relation and the gripping rods spaced apart. When the rods are thus spaced apart they clear the heads of the posts when lowered upon the mold, and when they are released from the locking bar, the spring means 55 urges the rods upon the post shanks underneath the heads.

The locking bar 56 is made to release the arms 54 by operation of a push bar 61 operable by a rod 62 projecting upward from the plate 42, to push the free end of the locking bar upward.

In operation, the gripping rods are normally held in spaced apart position, as shown in Figure 2. As the lower structure 40 is raised, the superstructure 41 is lowered in timed relation, to allow the gripping rods to descend past the post heads. When they reach proper gripping position, the push rod 61, actuated by the rod 62, lifts the locking bar 56, allowing the upper ends 54 of the arms to spread and allowing the springs 55 to draw the two gripping rods upon the interposed post shanks, underneath the post heads.

The post shanks of the second line of posts in the mold are gripped similarly by a second pair of gripping rods and supporting arms, which latter are suitably connected to the first pair of supporting arms by links 63.

After the gripping rods have gripped the battery posts, the sleeve 46 with the superstructure is raised, and the superstructure is swung sidewise for discharge of the battery posts into a suitable container.

As the superstructure approaches the end of its outward swing, the upward extensions 54 enter a wedge-shaped member 64, which crowds the upper ends of the arms toward one another, forcing the gripping rods 50 apart to release the battery posts and causing the locking bar 56 to re-engage the pins 60 for locking the arms in parallel position, with the gripping rods 50 ready for another operation.

The member 64 is supported on a fixed arm 65.

The drive means for the different parts of the apparatus have not been shown as coming well within ordinary engineering skill. It will be understood that the two turrets are rotated intermittently, at the same speed and in opposite directions, while all the other active members, such as the arm 37, the finger 24, the plunger 45, the sleeve 46 and its arm 48 are actuated by any suitable drive means to become active at the proper times to properly perform the functions assigned to them.

I claim:

1. In a lead casting machine, a member having a mold with a flat horizontal top surface mounted thereon and having mold cavities communicating with said surface, a vertical shaft mounted outside the member and having a disc 70 rotatable thereon, a block on the rim of the disc, a rod slidably radially in the block, spring means urging the rod radially inwardly, a second block mounted on the outer end of the rod, a gate secured upon the second block and adapted to over-

lie the mold, the gate having a flat bottom surface immediately adjacent said top surface and having openings positioned to register with the cavities and to allow the lead to be poured into the mold cavities, and means bearing on the gate at the time the gate is in operative relationship with the mold and operable for pushing the gate outwardly against the spring tension for shearing the lead between the mold and the gate.

2. In a lead casting machine, a member having a mold with a flat horizontal top surface mounted thereon and having mold cavities communicating with said surface, a vertical shaft mounted outside the member and having a disc thereon, a block on the rim of the disc, a rod slidably radially in the block, spring means urging the rod radially inwardly, a second block mounted on the outer end of the rod, a gate secured upon the second block and adapted to overlie the mold, the gate having a flat bottom surface immediately adjacent said top surface and having openings positioned to register with the cavities and to allow lead to be poured into the mold cavities, and means bearing on the gate at the time the gate is in operative relationship with the mold and operable for pushing the gate outwardly against the spring tension for shearing the lead between the mold and the gate, the shaft being revolvable for carrying the gate away from the mold circumferentially and the gate being hinged to the second block with freedom of downward swinging movement toward vertical position when it leaves the mold.

3. In a lead casting machine, a member having a mold with a flat horizontal top surface mounted thereon and having mold cavities communicating with said surface, a vertical shaft mounted outside the member and having a disc thereon, a block on the rim of the disc, a rod slidably radially in the block, spring means urging the rod radially inwardly, a second block mounted on the outer end of the rod, a gate secured upon the second block and adapted to overlie the mold, the gate having a flat bottom surface immediately adjacent said top surface and having openings positioned to register with the cavities and to allow lead to be poured into the mold cavities, and means bearing on the gate at the time the gate is in operative relationship with the mold and operable for pushing the gate outwardly against the spring tension for shearing the lead between the mold and the gate, the shaft being revolvable for carrying the gate away from the mold circumferentially and the gate being hinged to the second block with freedom of downward swinging movement toward vertical position when it leaves the mold, and the machine having means for locking the gate against swinging movement when it reaches a vertical position.

4. In a lead casting machine, a pair of revolvable discs mounted in horizontally spaced relation for revolvable movement about vertical axes, a mold projecting sidewise from one of the discs and having a flat horizontal face, a mold gate having a flat bottom face and being hingedly mounted with respect to the other disc for swinging movement in a vertical plane, means for intermittently revolving the discs for moving the mold and the gate circumferentially from station to station operable to bring the gate and the mold into registry at one of the stations, means for swinging the gate into horizontal position as it approaches said station, the gate being mounted at an elevation to overlie the mold at said station for a pouring operation, with the

bottom face of the gate in contact with the top face of the mold, and means for moving the gate at said station for shearing surplus metal from the mold.

5. In a lead casting machine according to claim 1, said member comprising a revolvable disk.

6. In a lead casting machine according to claim 3, means operable on the vertically disposed gate for ejecting surplus lead therefrom.
